(57) CLAIM

The ornamental design for display for wrist bands, as shown and described.

DESCRIPTION

FIG. 1 is a perspective view of a display for wrist bands.

FIG. 2 is a top view of the display of FIG. 1.

FIG. 3 is a front view of the display of FIG. 1.

FIG. 4 is a back view of the display of FIG. 1.

FIG. 5 is a bottom view of the display of FIG. 1.

FIG. 6 is a left side view of the display of FIG. 1.

FIG. 7 is a right side view of the display of FIG. 1; and, FIG. 8 is a perspective view of the display of FIG. 1 and shows wrist bands secured in place and a motion tracker device which is configured to be housed in the aperture of a wrist band.

The broken lines are for the purpose of illustrating the environment of the article only and form no part of the claimed design.
